UNITED STATES PATENT OFFICE.

CHARLES E. SHRINER AND FRANK A. SHRINER, OF MONROE, WISCONSIN, ASSIGNEES
OF ONE-THIRD TO FRIGID FLUID COMPANY, OF CHICAGO, ILLINOIS, A CORPORA-
TION OF ILLINOIS.

DASH-POT FOR CASKET-LOWERING DEVICES.

1,188,686.

Specification of Letters Patent. Patented June 27, 1916.

Application filed March 5, 1915. Serial No. 12,413.

To all whom it may concern:

Be it known that we, CHARLES E. SHRINER and FRANK A. SHRINER, both citizens of the United States, residing at Monroe, county 5 of Green, and State of Wisconsin, have invented certain new and useful Improvements in Dash-Pots for Casket-Lowering Devices, of which the following is a specification.

10 The present invention has reference to certain improvements in casket lowering devices of that general type in which the descent of the casket is resisted by hydrostatic pressure within a cylinder, the release of the 15 oil or other liquid from the cylinder permitting its plunger or piston to move inwardly under the force generated by the weight of the casket. In this class of device the hydrostatic pressure to which the plunger and cylinder must be subjected is dependent upon the total volume of liquid displaced during 20 the descent of the casket. Therefore, it is desirable to make this volume as large as possible in order to reduce the hydrostatic pressure to a reasonable amount. The volume of liquid displaced at each stroke of the 25 plunger is dependent upon the size of the cylinder. Therefore, in those forms of construction in which the volume of liquid within 30 the cylinder is displaced but once during a complete lowering operation, it is necessary to use a cylinder of undesirably large size or else to permit the hydrostatic pressure to reach an abnormal figure. As far as 35 we are aware, in all mechanisms heretofore devised in which the descent of the casket is resisted by the movement of a piston or plunger, such piston or plunger has been permitted to make only a single movement, 40 and, therefore, it is our belief that all previously devised mechanisms have been subject to the objection above outlined.

One of the objects of the present invention is to provide a construction such that the 45 hydrostatic pressure may be maintained within reasonable limits, while at the same time making use of a cylinder of whatever size may be found convenient or desirable. In accomplishing this object of the invention, we provide a construction such that the plunger or piston is enabled to accomplish as many complete strokes as may be desired, thereby making it possible to absorb the energy given up by the descent of the casket

even with a cylinder of very small size operating under a small hydrostatic pressure. 55

Another object of the invention is to provide a construction such that the descending of the casket will be perfectly uniform and regular without any jerking tendency whatsoever. This result we accomplish by reason of the peculiar relationship which is established between two or more pistons or plungers working within their respective cylinders. 60

Still another object of the invention is to provide means for very accurately controlling the speed at which the casket will be lowered, and in this connection to provide a construction such that the control of the 70 speed can be readily effectuated by means of a foot pedal or the like. 65

Other objects and uses will appear from a detailed description of the invention which consists in the features of construction and 75 combinations of parts hereinafter described and claimed.

Referring to the drawings: Figure 1 shows a plan view of the entire mechanism mounted in place with a casket supported by 80 the straps preparatory to commencing the lowering operation; Fig. 2 shows a side elevation corresponding to Fig. 1; Fig. 3 is a face view of the controlling mechanism; Fig. 4 is a side view corresponding to Fig. 3; Fig. 5 is a section taken on the line 5—5 of Fig. 4, looking in the direction of the arrows; and Fig. 6 is a section taken on the line 6—6 of Fig. 3, looking in the direction of the arrows. 85

In the several figures we have illustrated a 90 casket 9 as being supported by the straps 10 and 11. The frame of the device comprises the end portions 12 and 13 and the sides 14 and 15. It is desirable that each one of these should be extensible so that the size of the 95 frame can be adjusted according to the size of the grave. The details of construction of the frame will be presently described. At this point we will state that the side portions 14 and 15 rotate in opposite directions, 100 being drivingly connected together for this purpose by the end 13. The end 12 is conveniently constructed in the present case so as to serve merely as a brace or support for the ends of the portions 14 and 15 without 105 being drivingly connected to either of them.

At the two corners where the portions 14 and 15 adjoin the end 13 there are pro-

vided the box members 16 and 17. The member 13 is connected to a short shaft extending through the corresponding box, said shaft having a spiral gear working within 5 the box. This spiral gear, in turn, meshes with another spiral gear, which is drivingly connected to the sleeve 21 of the corresponding member 14 or 15. It is thus seen that the driving connections between the member 10 13 and the members 14 and 15 are effected through the boxes 17 and 16. Adjacent to the box 17 is mounted the energy absorber in the form of a hydrostatic plunger mechanism. For this purpose the box 17 has an 15 outwardly facing flange 23 to which is secured the absorber casing 24. The spiral gear is connected to a shaft or extension 27 which extends through the flange 23 and finds a bearing therein. Inside of the casing 24 a wrist plate 28 is secured to the extension 27, said wrist plate in turn carrying a crank pin 29. Within each cylinder there travels a piston 30 connected to its piston rod 31.

25 The side members 14 and 15 of the frame are preferably made up of the end tubular sections 21 and 47. A square or angular rod 48 slides within the tubular sections, passing through the blocks 49 which are provided 30 with square or angular perforations for the accommodation of the rods. These blocks are rigidly connected to the corresponding tubes. In order to maintain the rods 48 in alinement with their respective tubes we 35 prefer to provide the blocks 50 on their end portions. These blocks serve the function of limiting the amount by which the frame may be extended endwise.

The shafts, which carry the spiral gears, 40 are loosely connected to the tubular sections 51 and 52. This loose connection is preferably effected by pins 53 and 54, which pins serve to establish driving connections between the shafts and the tubular sections 45 while at the same time permitting said sections to twist with respect to the shafts. This will permit the parts to accommodate themselves to irregularities in the surface of the ground. The tubular section 52 is provided with a series of perforations 55 adapted 50 to receive a pin 56 which is extended through the tubular section 51 and drivingly connects the same with the tubular section 52. By means of this construction 55 the entire frame can adjust itself to inequalities in the surface of the ground so that the frame will lie in a warped plane. Nevertheless, the driving connection is always established and maintained between 60 the side portions 14 and 15.

For the purpose of rewinding the frame a crank 57 may be applied to any suitable point, but we have illustrated the same as applied to that portion of the shaft of the 65 side 14 which extends through the box 16.

The ports and valve control mechanism are so arranged that the oil circulates back and forth between the back ends of the cylinders in pairs. The cylinders 57, 58, 59, 60 are arranged in sets or pairs, said sets occupying positions diagonally opposite to each other. The plungers of each pair of cylinders are connected together through the medium of a rectangular box 61, and the crank pin carries blocks 62 working within 70 this box. It will, therefore, appear that the plungers of each pair of pistons will travel with a strictly sinusoidal movement, and inasmuch as the groups or pairs of cylinders are mounted at right angles to each other, 75 one or the other of said groups will always be in position to receive the thrust from the crank pin. The back ends of the cylinders 57 and 59 may be connected together by a port 63, and the back ends of the cylinders 58 and 60 may be connected together by another port 64 at right angles to the port 63. In the central portion of the device is mounted a plug valve 65 having the holes 66 and 67 cut through it at right angles to each other, said holes not communicating with each other, and also being in line with the ports 63 and 64 respectively. With this arrangement when the plug valve stands in one position, both of the ports 63 90 and 64 will be closed, whereas when the plug valve is rotated through 45°, both of these ports will be opened to the full extent. At intermediate positions of the plug valve, the openings will be greater or less. Inasmuch as the opposite pairs of pistons travel in unison, there will be perfect compensation or equalization of volume as between them, and thus the tendency toward the formation of air pockets will be obviated. 95 Furthermore, with this arrangement it is not necessary to fill the interior portions of the casing, nor is it necessary to permit circulation between said interior portion and the back ends of the cylinders. However, 100 the interior portion of the casing may be filled with oil if desired. As a simple means of controlling the plug valve, we have shown a lever arm 68 mounted on the same and a spring 69 whose function is to restore the 105 plug valve to closed position when the lever and arm is released.

With the mechanism embodying the features of invention herein disclosed, the rate of descent of the casket may be very nicely controlled, and, furthermore, the descent of the casket will be perfectly uniform by reason of the relative positioning of the cylinders and their pistons. Furthermore, the descent of the casket can be arrested at any 110 point because one of the pistons at least is always in position to receive the thrust or pull occasioned by the weight of the casket. This would not be true of an arrangement 115 embodying a single cylinder, inasmuch as 120 125 130

the piston must be more or less away from its positions of dead center in order for it to take up the thrust or pull. Nevertheless, we wish to point out the fact that certain features 5 of the invention do not require the use of two or more pistons, as, for example, the feature of permitting the piston to accomplish a large number of reciprocations during the descent of the casket as distinguished 10 from an arrangement in which the piston is permitted to accomplish only a single movement in one direction. Furthermore, the feature of providing for an equalization of the total inclosed volume at all times during 15 the piston movement so as to eliminate the creation of any open or unoccupied spaces may be accomplished without the necessity of using more than a single piston.

While we have herein shown and described 20 the essential features of our invention as applied to only a single construction or embodiment, still it will be understood that many changes or modifications may be made without departing from its spirit or scope. 25 Therefore, we do not limit ourselves to the construction illustrated and described except as we may do so in the claims, but we contemplate within the scope of our invention any equivalent mechanisms operating 30 in equivalent manners to produce equivalent results.

I claim:

1. In a device of the class described, the combination, with a shaft operatively connected to a part, said shaft being rotatable during the operation of said part, of a plurality of cylinders mounted in pairs with respect to said shaft, the cylinders of each pair being diametrically opposed to each 25

other, and the pairs of cylinders being at 40 different angular positions with respect to the shaft, a piston within each cylinder, the pistons of the pairs of cylinders being connected together and working in opposition, a crank pin connected to the shaft, operative 45 connections from the crank pin to the pairs of cylinders, there being fluid connections between the back ends of the cylinders of each pair, and means for controlling the flow of fluid through each of said connections, for the purpose specified. 50

2. In a device of the class described, the combination, with a shaft operatively connected to a part, said shaft being rotatable during the operation of said part, of a plurality of cylinders mounted in operative position with respect to said shaft, said cylinders being mounted in pairs, and the pairs of cylinders being at different angular positions with respect to the shaft, the cylinders of each pair being diametrically opposed to each other, a piston within each cylinder, the pistons of each pair of cylinders being directly connected together and working in opposition, a crank pin on the shaft, an operative connection from each of said connections to the crank pin, there being fluid connections between the back ends of the cylinders of each pair, said fluid connections being independent of each other, and 60 means for controlling the flow of fluid through said fluid connections, for the purpose specified. 65
